UNITED STATES PATENT OFFICE.

WILLIAM FRANCIS CONKLIN, OF TARENTUM, PENNSYLVANIA, ASSIGNOR TO WEST PENN STEEL COMPANY, OF BRACKENRIDGE, PENNSYLVANIA, A CORPORATION OF NEW JERSEY.

REPEATING MECHANISM FOR ROLLING-MILLS.

1,184,519.

Specification of Letters Patent.

Patented May 23, 1916.

Application filed June 29, 1915. Serial No. 36,960.

To all whom it may concern:

Be it known that I, WILLIAM F. CONKLIN, a citizen of the United States, residing at Tarentum, in the county of Allegheny and 5 State of Pennsylvania, have invented certain new and useful Improvements in Repeating Mechanism for Rolling-Mills, of which the following is a specification.

My invention relates to rolling mills for 10 plate or sheet metal.

It has for its object to provide a repeater which may be easily mounted on the ordinary housing of a two high mill for returning the sheets in front of the rolls, for re- 15 rolling, or so adjusted out of operative position, as to permit the sheets to pass directly through in the ordinary way.

The invention comprises an arc-shaped 20 guide frame having bearing rollers, pivotally mounted upon a supporting hanger frame for adjustable location with relation to the rolls and provided with an adjusting operating lever, as shall be more fully hereinafter described.

Preferred forms of the invention are 25 shown in the accompanying drawings, in which—

Figure 1 is a partial plan view illustrating 30 one of the supporting hangers and the operating lever. Fig. 2 is a sectional elevation showing the device mounted between the housings in operative relation to the rolls. Fig. 3 is a view similar to Fig. 2 illustrating 35 a construction utilizing an inner series of additional guide rollers. Fig. 4 is a view of the adjustable guiding mechanism and its parts, detached. Fig. 5 is an enlarged cross section, on the line V. V. of Fig. 2. Fig. 6 is a similar section on the line VI. VI. of 40 Fig. 3.

In the drawings, 2, 2, are the rolls mounted in the usual way between the ordinary 45 housings 3 of the mill, and having transverse tie rods or braces 4, 4.

Ordinarily, the plates or sheets are passed 50 through between the rolls 2 on the line a, a, from front to back, and are received on a table or other support beyond the roll train, from which they are ordinarily returned to 55 the front of the rolls for re-rolling, by hand. For the purpose of automatically returning the plates or sheets, after passing through the rolls, I provide an arc-shaped frame composed of two curved side plates 5, 5, 60 connected by suitable bolts 6 with interven-

ing braces, and having series of staggered disk rollers 7 pivotally mounted on studs 8 for free rotation between the sides 5. The peripheries of said rollers are thus arranged in an arc-shaped path around the periphery 60 of the upper roll, two such series being preferably provided, one at each side of the center, as indicated in Fig. 4, for ample engagement with the blank being rolled. Plates 5 have supporting extensions 9 embracing each side of a supporting bearing 10 forming part of the hanger 11, which in turn is carried by the tie rods 4, 4, of the 65 housings. The hanger 11 bears by its ends on said rods, and is provided with caps 12 and securing bolts 13, by which secure attachment may be made, with ample provision for adjustment to variations in the rods 4, or for adjustment thereon with relation to the rolls. Hangers 10, there being 70 15 one at each side for each pair of plates 5, 5, are provided with suspending eyes 14, 14, for attachment to a crane or the like.

For the purpose of providing pivotal adjustment for the arc-shaped frame (5, 5), its 75 supporting extensions 9 are pivotally hung upon stud extensions 15 having terminal bolt ends 16 (squared or slotted for a wrench or screw driver), and extending eccentrically 80 of a cylindrical barrel 17 mounted in bearing 10. A set screw 18 fixedly holds said barrel in position, so that it may be turned 85 to the desired degree and there held. By this means the arc-shaped guide roller frames may be accurately adjusted with relation to the rolls.

Beyond the pivotal mounting of the roller carrying frames, they are provided with extensions or lugs 19, secured in any suitable manner and adapted to receive and support 90 at one or both end portions of the entire tilting structure, an actuating rod or bar 20. Said bar extends across the ends of all of the plates 5, is preferably squared or splined, and is fixedly secured in the several lugs 19, 95 so that when power is imparted to the bar, it will rock the entire frame upwardly or downwardly as to the series of rollers 7, on the pivoting supports 15. For the purpose of thus actuating the frame, bar 20 is provided at one end with an operating lever 21, which has a limited range of lateral movement on the end of the bar by clearance 22, and is secured to the bar by a pin 23. The 100 lever 21 extends beyond the housing, pro- 105 110

viding a handle by its terminal, and is operable vertically along the inner face of a guiding and limiting frame member 24, which may conveniently be of angle form, bolted to the inner edge of the housing, as clearly shown.

Extending inwardly of frame 24 are limiting pins or abutments 25, 25, at the upper end and 26 at the lower end. By this means 10 the entire frame may be tilted upwardly out of the range of the blank, as indicated in dotted lines in Fig. 2, and there held by pin 26, or may be lowered to operative position, and lever 21 fixedly held between the adjacent studs 25.

For the purpose of insuring engagement with the studs or pins 25, 26, after the raising or lowering operation, and of positively thrusting the lever toward the inner face of 20 frame 24, I provide a spring 27 surrounding bar 20, bearing by its inner end against a collar 28 on the shaft, and by its outer end against a sliding collar 29. Said collar 29, being non-rotatably mounted on bar 20, as 25 by a squared or splined opening, is chamfered off at its inner portion, providing clearance 30, whereby its outer portion will always bear with a defined leverage against the hub of lever 21, whereby to thrust it outwardly toward the face of frame 24, thus 30 insuring engagement with the pin or pins.

The lower ends of roller carrying frames 5, 5, are provided with terminal blocks 31, 25 adapted to provide an initial bearing surface for the edge of the plate and to deflect it upwardly around the upper roll and against the series of rolls 7. Said bearing terminal 31 is adjustably mounted between the side plates 5 by means of bolts 32 having 40 slotted engagement with the plates, whereby to compensate for wear and relocate the block, as desired.

The construction and operation of the mechanism as illustrated in Figs. 1 and 2 45 will be readily understood and appreciated from the foregoing description.

In Figs. 3 and 4, the same general arrangement of parts is shown, and identified by corresponding numerals having the exponent *a*. These figures also show the use of a 50 series of supplemental inner guide rollers 33, so arranged with relation to the rollers 7^a as to provide between them an arc-shaped path for the passage of the blank. This 55 arrangement is desirable at times in the case of rolling very thin sheets, or where there is liability to buckle or unduly curve toward the upper roll 2^a, and whereby to positively provide a limiting open pathway for the 60 blank, in returning it to the front of the rolls. In such case rollers 33 are mounted on carrying studs 34 mounted in an arc-shaped frame 35 connected with the main frames 5^a, by arms 36 extending outwardly 65 and backwardly and secured by the cross

shafts 6^a of the general framework construction, as clearly shown in Fig. 6. By this means the inner series of rollers 33 are fixedly held with relation to the outer rollers 7^a, and the entire structure may be actuated in the manner already described. I preferably provide, at the end of frames 35, 70 terminal bearing blocks 37, which may engage against the face of the upper roll, whereby to positively deflect the blank into the arc-shaped guiding passageway. The 75 construction and operation otherwise is substantially the same as in the simpler form above described, and capable of the same range of movement and adjustment.

The advantages of the invention reside in its facility for returning light plates or sheets of metal automatically for re-rolling. The construction is such as to adapt it to mounting between the housings of an ordinary roll train, without any specially designed supporting mechanism, and enabling the easy application and removal of the device, and its utilization with various standard constructions of mill practice, due to its 85 construction and manner of mounting. This is of especial advantage in connection with the usual and necessarily frequent and rapid change of rolls of the mill, the entire structure being readily lifted away, merely by 90 removal of the caps 12 and adjustment of lever or levers 21, utilizing a crane and the supporting eyes 14.

The accurate and rapid adjustment provided for by the eccentric mounting of the 100 pivoted roller frames enables the operator to adjust the mechanism to the different conditions of use. The spring actuated operating lever insures positive holding of the frame in raised or lowered position and 105 against accidental displacement.

The advantages of the invention will be readily appreciated by all those familiar with the rolling of sheet metal; it may be changed or varied in construction or adaptation to various conditions of use by the skilled mechanic; and I do not desire to be limited to the specific construction and arrangement shown, except as required by the appended claims.

What I claim is:

1. Repeater mechanism for reducing rolls, comprising a rigid arc-shaped frame adapted to be pivotally supported above the rolls and provided with a series of guiding rollers.

2. Repeater mechanism for reducing rolls, comprising a rigid arc-shaped frame adapted to be pivotally supported above the rolls and provided with a series of guiding rollers, and an operating lever for locating the frame 125 in varying positions.

3. Repeater mechanism for reducing rolls, comprising a rigid arc-shaped frame adapted to be pivotally supported above the rolls and provided with a series of guiding rollers,

- an operating lever for locating the frame in varying positions, and means for fixedly holding the mechanism in adjusted position. 5
4. Repeater mechanism for reducing rolls, comprising a rigid arc-shaped frame adapted to be pivotally supported above the rolls and provided with a series of guiding rollers, and means for varying the position of the pivotal support. 10
- 10 5. Repeater mechanism for a rolling mill comprising an arc-shaped frame having a series of guiding rollers, an operating lever, and supporting mechanism therefor embodying eccentrically adjustable pivoting devices. 15
- 15 6. Repeater mechanism for a rolling mill comprising an arc-shaped frame having a series of guiding rollers, an operating lever, supporting mechanism therefor embodying eccentrically adjustable pivoting devices, 20 and means for fixedly holding said eccentric mechanism in varying positions. 25
7. Repeater mechanism for a rolling mill comprising an arc-shaped frame having a series of guiding rollers, an operating lever, supporting mechanism therefor embodying eccentrically adjustable pivoting devices, and a superimposed supporting yoke having means for attachment to elements of a mill. 30
8. In combination, a supporting yoke having removable caps and an intervening bearing portion, adjustable eccentrically mounted pivoting mechanism, an arc-shaped frame pivotally mounted thereon provided with a series of guiding rollers, and means for tilting and fixedly holding said frame in position. 35
9. In combination with rolls and housings therefor, and elements connecting the housings; a removable supporting frame mounted on said elements provided with an intervening bearing portion, adjustable eccentric mechanism therein having pivoting studs, and an arc-shaped frame pivotally mounted thereon provided with a series of guiding 40 rolls and an operating lever. 45
10. In combination with rolls and housings therefor, and elements connecting the housings; a removable supporting frame mounted on said elements provided with an intervening bearing portion, adjustable eccentric mechanism therein having pivoting studs, and an arc-shaped frame pivotally mounted thereon provided with a series of guiding 50

rolls and an operating lever and a terminal bearing block. 55

11. The combination with the housings and the pivoting support carried thereby, of a tilting repeater frame having guiding rollers, an operating lever therefor, and a guide plate secured to the housing having limiting abutments adapted to engage said lever. 60

12. The combination with the pivotally mounted repeater frame having a series of guiding rollers, of a laterally adjustable actuating lever adapted to swing said frame on its pivotal mounting, limiting abutments for said lever, and spring mechanism adapted to thrust the lever laterally into engagement therewith. 65

13. Repeater mechanism for reducing rolls, comprising a rigid arc-shaped frame adapted to be pivotally supported above the rolls and provided with adjacent series of guiding rollers providing an arc-shaped guiding passageway for the blank. 70

14. Repeater mechanism for reducing rolls, comprising a rigid arc-shaped frame adapted to be pivotally supported above the rolls and provided with a plurality of series of guiding rollers and an intervening passageway, and an operating lever for locating the frame in varying positions. 80

15. Repeater mechanism for reducing rolls, comprising a rigid arc-shaped frame adapted to be pivotally supported above the rolls and provided with a series of guiding rollers, a similar frame connected to said frame having a series of guiding rollers spaced away from said first named rollers, an operating lever for locating the frame in varying positions, and means for fixedly holding the mechanism in adjusted position. 85 90

16. Repeater mechanism for reducing rolls, comprising a rigid arc-shaped compound frame adapted to be pivotally supported above the rolls and provided with a plurality of adjacent spaced series of guiding rollers, and means for varying the position of the pivotal support. 95

In testimony whereof I hereunto affix my signature in the presence of two witnesses. 100

WILLIAM FRANCIS CONKLIN.
